UNITED STATES PATENT OFFICE.

ARTHUR G. HATCH, OF DULUTH, MINNESOTA.

SADDLE FOR REENFORCING BARS.

1,406,379.

Specification of Letters Patent. Patented Feb. 14, 1922.

Application filed March 28, 1921. Serial No. 456,399.

To all whom it may concern:

Be it known that I, ARTHUR G. HATCH, a citizen of the United States, residing at Duluth, in the county of St. Louis and State 5 of Minnesota, have invented certain new and useful Improvements in Saddles for Reenforcing Bars, of which the following is a specification.

This invention relates to a new and improved saddle for reenforcing bars, and more particularly to a device of the class described which is adapted to be attached to the bars and is further provided with means for preserving the spacing of adjacent bars.

In the use of steel bars in reenforcing concrete, it is necessary that the bars be maintained a predetermined distance above the lower face of the concrete in order that 20 they may be sufficiently surrounded by the concrete to be able to render their maximum efficiency. It has been general practice heretofore to provide various forms of chairs or saddles which have usually been either fastened to the forms or placed loosely thereon. These saddles have not been generally connected to the reenforcing bars.

It is an object of the present invention to provide a form of saddle for reenforcing bars 30 having a turn adapted to encircle the bar sufficiently to maintain the saddle in engagement therewith, and to provide a plurality of spaced bar seats.

It is a further object to provide a saddle 35 which when so attached to the bar will normally maintain a proper position for supporting the bar.

It is an additional object to provide a saddle 40 of this type which is provided with means adapted to prevent adjacent bars from moving closer together than a predetermined distance.

It is also an object to provide a saddle 45 which is simple in design and cheap in construction and which may be readily attached to or detached from the reenforcing bars.

Other and further objects will appear as the description proceeds.

Broadly, my saddle comprises a piece of 50 bent wire or strip metal formed in a manner to encircle a reenforcing bar and provide a plurality of spaced feet extending below the bar. Additional features comprise the fact that the turn about the bar is of sufficient length to provide two spaced seating surfaces, and further in that in the preferred

form one at least of the supporting legs has a portion thereof formed to engage an adjacent bar to prevent the bars being forced too close together.

I have illustrated certain preferred embodiments of my invention in the accompanying drawings, in which—

Figure 1 is a cross section showing a number of reenforcing bars in relation to the forms for the concrete;

Figure 2 is a plan view of Figure 1;

Figure 3 is a fragmentary view similar to Figure 1 and showing a modified form of the device; and

Figure 4 is a view similar to Figure 3 showing a further modification.

Referring first to Figure 1, the spaced forms 5 and 6 adapted to contain between them a concrete beam, are supported upon the framework 7. The reenforcing bars 8 and 9 are located within the forms in a position to properly reinforce the beam to be cast therein. The bar 8, as shown in Figures 1 and 2, is supported upon chairs or saddles. These saddles 10 comprise a left leg 11 which extends diagonally upward to the bar 8 and then continues as a curved seat 12 under the bar. The turn of the member continues the curves 12 spirally about the bar 8 to form a second seat under the bar and from the point 13 it extends downwardly to form the right leg 14. After making contact with the forms at 15, the right leg turns upwardly to form a vertical finger 16 which extends into the plane of the bars 8 and 9. The saddles for the bar 9 are similar to that just described, with the exception that the right leg 16 is not extended to form the spacing finger.

The form of the device shown in Figure 3 is similar to that shown in Figures 1 and 2, with the exception that the right leg 14' has a flat portion 17 in engagement with the form 5'. This portion is of sufficient length 100 so that the spacing finger 16' engages the bar 9' to maintain it at the proper distance from the bar 8'.

The form of saddle shown in Figure 4 differs somewhat from that described in that 105 the turn about the bar 18 continues up to the point 19 and the saddle then extends laterally at 20 and is formed with a depression 21 to receive the second bar 22. The saddle then extends downwardly to form the right 110 leg 23.

It will be seen that in all forms of my de-

vice, the saddle provides two spaced seating curves for the bar, due to the fact that the saddle is continued around the bar spirally for a distance greater than one complete circle. It is to be understood that the special form of the device shown in Figure 4 may be placed upon either bar, or both bars in reverse direction, so that certain of the saddles may be retained upon one bar 10 and others upon the other bar. Saddles with spacing elements may be used exclusively or in combination with the simple form of the saddles.

The form of saddle shown at the left of Figure 1 may be provided with a spacing finger at a distance from the bar governed by the minimum allowable spacing for bars in the concrete, or as shown in Figure 3, the finger may be spaced at any specific distance in order to positively space the bars 20 that distance.

In the form of Figure 1, it is simply intended to prevent a dangerous amount of relative displacement of the bars; while in Figure 3 it is intended to positively space the bars. The form shown in Figure 4 positively spaces the bars.

All these forms of saddles are formed of relatively light wire and may be shipped in a condition with the bar-engaging loop somewhat open, and may thus be readily applied to the bars and brought to shape manually. An important feature of the form of the device shown in Figures 1 to 3 particularly lies in the fact that if the saddles are applied to the bars with a slight looseness, they will be swung by gravity to the proper position and the bars may then be quickly placed in the forms without the necessity for attention to each individual saddle.

These forms of saddles may be easily and cheaply manufactured from standard sizes

of wire and may be readily applied by unskilled labor, and will positively locate the bars properly in the concrete and efficiently 45 maintain the bars in spaced relation against any displacing thrust, due to the pouring of the concrete.

I claim:

1. A saddle for reenforcing bars, comprising a continuous member forming a pair of spaced supporting legs joined by an open spiral connecting portion of more than one turn forming a plurality of spaced seats for the bar and maintaining the bar in the seats. 50

2. A saddle for reenforcing bars, comprising a continuous member forming a pair of spaced supporting legs joined by an open spiral connecting portion of more than one turn forming a plurality of spaced seats for 60 the bar and maintaining the bar in the seats, the legs extending from the connecting portion upon opposite sides of the seat portions and upon approximately radial lines.

3. A saddle for reenforcing bars, comprising a continuous member forming legs, and a seat for a bar, one of said legs being extended upwardly from its foot to engage another bar located approximately parallel to the first bar to limit movement of the two 70 bars toward each other.

4. A saddle for reenforcing bars, comprising a continuous member forming legs, the portion intermediate said legs being a loop of more than a complete circumference 75 adapted to form a plurality of spaced seats for a bar, and one of said legs being extended upwardly from its foot to engage another bar located approximately parallel to the first bar to limit movement of the two 80 bars toward each other.

Signed at Duluth, Minnesota, this 21st day of March, 1921,

ARTHUR G. HATCH.
